(57) **CLAIM**

The ornamental design for a cover for pet fountain, as shown and described.

DESCRIPTION

FIG. 1 is a front, top, right side perspective view of a cover for pet fountain incorporating our new design, shown in use; FIG. 2 is another perspective view thereof; FIG. 3 is a front elevation view of the cover of FIG. 2; FIG. 4 is a rear elevation view of the cover of FIG. 2; FIG. 5 is a top plan view of the cover of FIG. 2; FIG. 6 is a right side elevation view of the cover of FIG. 2; and, FIG. 7 is a bottom plan view of the cover of FIG. 2.

The left side elevation view of the cover is identical to that shown in FIG. 6.

Broken lines and portions contained within broken lines are not claimed.

1 Claim, 3 Drawing Sheets
